**ATTACHMENT FOR CHASING THREADS
ON HORIZONTAL LATHES**

Pietro Ciccarelli, Genoa-Sampierdarena, Italy, assignor to
Instituto Salesiano Rebaudengo, Turin, Italy
Original application Apr. 6, 1956, Ser. No. 576,565.
Divided and this application Nov. 13, 1962, Ser.
No. 237,209

9 Claims. (Cl. 82—5)

This application is a division of my corresponding application Serial Number 576,565, filed April 6, 1956, now Patent No. 3,073,194 issued January 15, 1963, and is directed more specifically to the construction shown on FIGURES 4, 5 and 6 of the parent application.

It is the chief object of the invention to provide a thread-chasing attachment which may be applied to existing lathes equipped with a feed screw and which, once adjusted for any particular set-up, will operate semi-automatically, and with a minimum of attention to complete the threads of each individual workpiece.

Another object is to provide in a thread-chasing attachment of the type mentioned, a cross-feed for the tool which operates to condition and determine the amount or distance of advance of the tool toward the work by and in response to movement of the longitudinal slide and the tool carrier into final position during each working stroke.

A still further object is to provide a chasing attachment as in the preceding paragraph wherein the actual advance of the tool toward the workpiece, or the axis rotation thereof is effected by means which become operative on initial movement of the slide and carrier in the retrograde or return direction of translation parallel with the axis of rotation of the work.

Yet another object is to provide a thread-chasing attachment which makes it possible to vary, in a simple way, the distance of advance of the tool toward the work, for each stroke of the longitudinal slide.

Another object is to provide a thread-chasing attachment as aforementioned, wherein the tool is automatically rendered incapable of further cutting by and in response to completion of the threads to a pre-set or predetermined depth or in other words, to a pre-set maximum advance of the tool toward or into the workpiece.

Still another object is to provide a thread-chasing attachment which is quickly, easily, surely and accurately reset for operation upon the next workpiece, after completion of the previous one.

Another object is to provide an attachment of the nature disclosed, which is relatively simple and inexpensive to produce, reliable and accurate in use, quickly attached to and adjusted for use in connection with an existing lathe equipped with a feed screw, and versatile over a wide range of conditions of use.

Other objects and advantages of the invention will become obvious to those skilled in the art, after a study of the following detailed description, in connection with the accompanying drawing.

In the drawing:

FIGURE 1 is a vertical longitudinal section taken in a plane identified by the line I—I of FIGURE 3;

FIGURE 2 is an elevational view of the assembly of FIGURE 1, the front wall of the enclosure for the mechanism feeding the tool carrier toward the workpiece being removed;

FIGURE 3 is a plan view of the attachment parts being broken away to more clearly disclose important features;

FIGURE 4 is a detail view, partly broken away, showing the invention;

FIGURE 5 is a section taken in a plane identified by line 5—5 of FIGURE 6; and

2

FIGURE 6 is a top plan detail of the manual adjusting means for the depth of cut.

Referring in detail to the drawing, 1 identifies one end of a telescopic transmission shaft, connected by a universal joint 1a to rotate a worm, not shown, in mesh with a gear 2 forming a part of the invention. The other end of shaft 1 is connected to be driven by and from the feed shaft of a lathe, as shown and described in British Patent 764,926, so that gear 2 is rotated in timed relation therewith.

The base or frame of the attachment is identified as 1b, FIGURES 1 and 2 and is adapted for fixedly mounting upon the bed or the carriage of a lathe of conventional construction. Gear 2 is keyed to a vertical shaft 3 journaled by antifriction bearing 1c and 1d for rotation about a vertical axis in base 1b. The upper end of the shaft protrudes into the casing and has a specially shaped and constructed cam 4 removably fixed to its upper end as by cap screw 4b.

A slide 6 is mounted upon base 1b for guided horizontal translation in a direction which in normal operation, is parallel with the axis of rotation of a workpiece mounted between lathe centers. A roller or cam follower 5 is journaled on slide 6 for engagement with the periphery of cam 4 so that, in a manner clear from inspection of FIGURE 3, the slide is translated leftwardly, as viewed in this figure, by and in response to rotation of the cam in the direction of the arrow.

A transverse carriage or tool carrier 7 is mounted upon slide 6 for guided movement in a second direction perpendicular to the direction of translation of slide 6 upon base 1b. In normal operation, this second direction is toward and from the axis of rotation of the workpiece.

Referring especially to FIGURES 1 and 3, a bar 9 is mounted in guideways 9a fixed to the under side of slide 6, for translation relatively to the slide in the direction parallel with the direction of movement of slide 6 upon base 1b. At its right end as seen upon FIGURES 1 and 3, this bar carries a roller 8 adapted to be periodically engaged by a portion 4a of cam 4, as subsequently described. It should be particularly noted upon FIG. 3, that roller 5 is not journaled on bar 9 but is pivoted to the under side of slide 6. The left end of bar 9 is formed with an upwardly-facing channel 9b which, as clearly as shown upon FIGURE 3, extends at an angle, both to the direction of movement of slide 6 upon base 1b and of carrier 7 upon and relatively to the slide. Carrier 7 is provided with pin 11. A follower 10 is journaled for rotation upon the lower end of this pin and has a smooth fit within channel 9b so that, as bar 9 is translated relatively to slide 6, carrier 7 is correspondingly moved relatively to the slide, that is, toward and from the axis of rotation of the workpiece mounted between centers in the lathe. A coil spring 12, FIGURES 1 and 3, is mounted within a channel or recess in the under side of slide 6 and engages the left end of the recess. At its right end the spring engages an abutment 9c fixed with bar 9, to thus urge the bar toward the right, on and relatively to slide 6.

In addition to its periphery shaped essentially as shown at FIGURE 3, cam 4 is provided on its lower face with a bar-actuating portion or face 4a. As seen upon FIGURE 1, this portion lies in a plane axially and downwardly offset from the plane of the cam 4. As seen upon FIGURE 3, the portion 4a is not continuous, but to the contrary, extends over and is effective during only a relatively small angle of rotation of the cam, so that roller 8, previously identified, is positioned on bar 9 in the plane of rotation of cam position 4a, to be engaged thereby substantially at the instant the greatest radial dimension of cam 4 is effective upon follower 5, or, in other words, at the instant slide 6 reaches its extreme leftward position

during the working stroke. At this instant the bar 9 is thereby shifted leftwardly a short distance relatively to slide 6, and, due to the action of channel 9b on block 10, carriage 7 is retracted from the workpiece to withdraw therefrom a tool, not shown, mounted upon the carriage.

By the construction just described, the slide 6, carriage 7 and tool, are translated by cam 4 in the direction parallel with the axis of rotation of the workpiece in a working stroke, and in timed relation with such rotation. The numerical value of such timed relation will, of course, depend upon the pitch of the threads being cut and is varied by the change gears of the lathe itself. At the end of the working stroke, portion 4a engages roller 8 and acts positively to retract the tool from the work and to maintain it retracted until the slide has completed its retrograde or return movement.

This return movement is effected by a pair of identical coil springs, one of which 13a is shown at FIGURE 1 and the other of which 13, is shown upon FIGURE 2. Each spring surrounds a respective one of two rods 6a and 6b fixed in the right end of slide 6 and against which the springs abut at their right ends. The other or left ends of the springs abut base 1b, so that the slide is continuously urged to the right, that is, in retrograde translation.

The means for automatically advancing the tool into the work by predetermined increments is shown upon FIGURES 4, 5 and 6. In the embodiment shown, the carrier 7 has an extension 7a, FIGURES 5 and 6. A shaft 33 is journaled in this extension, for rotation upon a horizontal axis parallel with the direction of translation of carrier 7 on and relatively to slide 6. A combined ratchet wheel and cam element 30 is fixed to the inner or forward end of the shaft. The cam is identified at 30a and comprises a surface in the form of a helix about the axis of rotation of the shaft. At its forward end this helical surface terminates abruptly in an end surface, or shoulder disposed substantially in a radial plane through the axis of shaft 33 and extends from the shoulder at a constant helix angle or pitch to a point about 360° from the shoulder, at which point the surface merges smoothly into the contiguous face of the ratchet wheel. The exposed outer or rearward end of the shaft has a knurled knob 32 fixed thereto, which, as seen upon FIGURE 6 is provided with graduations readable against an index fixed with extension 7a whereby fine measured adjustments or rotations of cam 30a may be effected. The ratchet wheel itself has teeth extending over a portion only of its periphery. The remaining portions of its periphery is smooth and unaffected by reciprocations of plunger 34, FIG. 4.

The depth of cut for any given work stroke is determined by the angular rotation of cam 30a for each stroke or reciprocation of the slide. The amount of this rotation, of course, depends in any given set-up, upon the adjusted position of abutment 38. Thus carrier 7 and the tool fixed thereto move toward the work at the beginning of each working stroke, until cam 30a engages a follower 31 removably fixed with slide 6. This follower is offset slightly below shaft 33 so that turning of the shaft effects a fine controlled adjustment of the carrier toward the axis of rotation of the workpiece. The follower has a short section of helicoidal surface formed at the same helix angle as that of cam 30a, so that the two are in contact over a substantial area to reduce pressure and wear. The graduations on knob 32 may be in terms of the linear distances of advance of carrier 7 toward and from the axis of rotation of the workpiece.

Carrier 7 has a bore 6c the axis of which lies in a vertical plane normal to the direction of its movement on slide 6 and is inclined in said plane downwardly and to the left, as appears from inspection of FIGURE 4. It should be added that the aforesaid vertical plane also contains the ratchet wheel 30.

A plunger 34 is mounted within bore 6c FIG. 4, for

smooth guided movement axially there along. Any suitable means, not shown, are provided for preventing rotation of the plunger in the bore. The midportion of the plunger is recessed to receive a pawl 35 having one end pivoted within the recess for movement about an axis normal to the axis of the bore. A leaf spring interposed between the recess and pawl urges the other end thereof into engagement with ratchet wheel 30. The upper end or right end of bore 6c, as seen upon FIGURE 4, is closed by a plug 37. A coil spring 36 housed in the bore, acts between the plug and plunger to urge the latter toward the left.

The lower or left end of the plunger is reduced, as shown at 34a to form a shoulder which engages the left end of the bore to thus limit the movement of the plunger in this direction. The reduced end of the plunger is positioned to engage an abutment 38 for limited guided movement horizontally in and along a guide channel or groove 40 in base 1b. A set screw 39 acts to fix the abutment in a selected position of adjustment in and along the channel. The relative positions and relations of the parts are such that the reduced end 34a of plunger 34 engages abutment 38, as slide 6 approaches its final leftward position during a working stroke. The precise point of engagement may be varied by a corresponding adjustment of the abutment. On engagement of the plunger with the abutment, further leftward movement of slide 6 causes the plunger to move to the right relatively to the slide, so that the pawl 35 rides freely over a predetermined or desired number of the teeth of ratchet wheel 30 and of course, without rotating the wheel. At the instant the slide moves into final position, cam portion 4a acts to retract carriage 7 and the tool mounted thereon, as well as cam 30a from the follower 31 it will be understood that the surface of abutment 38 engaged by the end 34a of plunger 34, has a dimension in a plane normal to the plane of FIG. 4 so that end 34a will engage the surface for the limited range of movement of carrier 7 on and relative to slide 6.

As soon as cam 4, in its continued rotation in timed relation with rotation of the workpiece, permits initiation of return or retrograde movement of the slide under urge of springs 13a, spring 36 acts upon plunger 34 to move the same to the left relatively to slide 6. As a result pawl 35 effects clockwise rotation through a limited angle of ratchet wheel 30 and cam 30a. Rotation of the helicoidal cam is such as to enable the spring 12 when it becomes effective on separation of cam surface 4a from follower 8, to shift carriage 7 forwardly toward the workpiece through a distance proportional, for any given instrument to the number of teeth of wheel 30 traversed by ratchet 35. It will be understood that the cam 30a and follower 31 are out of contact at this time so that a very slight torque is sufficient to rotate shaft 33.

It has been explained that ratchet wheel 30a has a portion of its periphery blank or smooth so that pawl 35 is ineffective thereon. A satisfactory relation is such that this smooth portion is presented to pawl 35 coincident with the rotational position of helicoidal surface 30a enabling maximum advance of carrier 7 toward the axis of rotation of the workpiece. Thus in an obvious way, the scale on knob 32 may be directly in terms of the depth of thread to be cut.

The operation will be clear from the foregoing description, and is resumed as follows:

Base 1a is fixed to the lathe cross slide, in position such that slide 6 moves parallel with the axis of rotation of the work and carriage 7 moves toward and from the axis. With the part to be threaded mounted between lathe centers, the operator adjusts abutment 38 to a position which will give the desired advance of the tool into the work for each stroke of the slide. The advance will, of course, depend upon the material of the workpiece, the

type and size of threads to be chased, etc. If desired, this adjustment may be facilitated by a scale fixed along channel recess 40 and an index fixed with the abutment for movement along the scale.

Cam 4 is rotated from the feed screw of the lathe until slide 6 is in its extreme leftward position, so that plunger 34 is in its limiting position to the right within bore 6c and the lathe carriage is adjusted until the tool on carriage 7 is at the left end of the portion of the workpiece to be threaded. The change gears of the lathe are then meshed to give the proper, preselected speed ratio between the feed screw and chuck. This will, of course, depend upon the pitch or helix angle of the threads to be cut. Cam 30a is adjusted, by rotation of knob 32, until the cam follower 31 rests on a certain portion of the helicoidal surface of the cam. This position of adjustment is such that, on continued rotation of the cam, the tool will have been let into the work by a distance equal to the depth of the threads to be cut, at the instant the smooth or toothless portion of ratchet wheel 30 moves into contact with pawl 35, and is readily determined by the graduated scale of knob 32. With the lathe cross slide adjusted so that the tool is out of contact with the workpiece, the lathe is operated to bring slide 6 to its extreme right position, ready to start a work stroke. The lathe slides are adjusted to bring the tool into contact with the work surface to be threaded at the right end of the surface to be threaded. Knob 32 is adjusted for the depth of the first cut. The feed screw is connected with the power drive and the motor is started. As slide 6 approaches its final position in a work stroke, end 34a of plunger 34 is engaged by abutment 38 and moved against the urge of spring 36 by a distance and over a number of teeth on ratchet wheel 30a, predetermined by the preliminary adjustment of the abutment, as described. At the instant carriage 7 arrives at the end of its cutting or working stroke, it is retracted by cam portion 4a. Thereafter, as slide 6 begins its retrograde translation under the thrust of springs 13 and 13a, plunger 34 moves to the left in and along its bore, and cam 30a is rotated so that when carriage 7 is released by cam surface 4a, it is moved by spring 12 to advance the carrier and tool fixed thereto by the predetermined distance before the cam engages follower 31.

At the instant the slide has completed its retrograde translation, cam portion 4a rides off roller 8 and the tool is advanced into the work to make a new cut. The cycle is then repeated. At the instant that the thread has been completed to the desired depth, the smooth or toothless portion of the periphery of wheel 30 is presented to pawl 35 so that the latter is ineffective to further rotate the wheel. Consequently, no damage to the work can occur by letting the slide make one or more additional strokes.

As soon as the thread has been thus completed, the workpiece is replaced by another, knob 32 is reset, and the lathe is again set in operation. Thus the operation once started is completed automatically and the operator is not required to give constant attention thereto. When the thread is completed, further cutting ceases even although the slide continues to reciprocate under rotation of cam 4.

Many other ways of utilizing the invention will be obvious to those skilled in the art, after a study of the foregoing description. Likewise, modification and substitutions of equivalents will be obvious. Therefor, the description should be taken in an illustrative rather than a limiting sense.

Having thus fully disclosed the invention what I claim is:

1. In a threading attachment for a lathe adapted to mount and rotate a workpiece about the conventional axis of rotation of a lathe, a base, a slide mounted on said base for guided translation in a first path, a tool carrier mounted on said slide for guided translation in a second path toward and from said first path, a helicoidal cam journaled on said carrier for rotation about an

axis parallel with said second path, and engaging said slide, rotation of said cam effecting advance of said carrier transversely of said first path, a ratchet wheel fixed with said cam, pawl means carried by said slide for translation with respect thereto, and engaging said ratchet wheel, an abutment fixed with said base and, in response to translation of said slide, moving said pawl means in one direction to pass freely over said ratchet wheel without rotating the same, and spring means engaging and urging said pawl means in the opposite direction of movement to thereby rotate said ratchet wheel and said cam as said slide recedes from said abutment.

2. In a threading attachment for a lathe adapted to mount and rotate a workpiece about the conventional axis of rotation of a lathe, a fixed base, a slide mounted on said base for guided translation in a first path, a tool carrier mounted on said slide for guided translation in a second path toward and from said first path, a helicoidal cam journaled on said carrier for rotation about an axis parallel with said second path and rotatably engaging said slide, said cam being rotatable to effect movement of said carrier transversely of said first path, an abutment fixed with said base, a plunger movably carried by said slide, spring means urging said plunger in one direction of movement, said plunger engaging and being moved by said abutment, against the urge of said spring means, as said slide moves into final position in a working stroke, ratchet and pawl means between said plunger and said cam and operable to rotate the latter under urge of said spring means as said slide recedes from said abutment in retrograde translation, and means translating said slide in working and retrograde movements.

3. In a threading attachment for a lathe adapted to mount and rotate a workpiece about the conventional axis of rotation of a lathe, a base, a slide mounted on said base for guided reciprocation in a first path, a tool carrier mounted on said slide for guided translation in a second path, toward and from said first axis, and spring-urged toward said first path a unitary ratchet wheel and cam element journaled on said carrier for rotation about an axis parallel with said second path and engaging said slide, rotation of said cam permitting and controlling advance of said carrier along said second path, a plunger mounted on said slide for reciprocation in a plane normal to said second path, spring means urging said plunger in the direction corresponding to translation of said slide in a working stroke, an abutment fixed with said base and engaging and moving said plunger against the urge of said spring means, as said slide approaches final position in a working stroke, a pawl carried by said plunger and engaging and rotating said ratchet wheel as said slide recedes from said abutment in a retrograde stroke, and means reciprocating said slide in timed relation with rotation of said workpiece.

4. A threading attachment as in claim 3, said abutment being mounted to said base for adjustment in and along said first path, and means releasably, fixing said abutment to said base in adjusted position to correspondingly vary the stroke of said plunger.

5. In a threading attachment for a lathe adapted to mount and rotate a workpiece about the conventional axis of rotation of a lathe, a base, a slide carried by said base for guided translation in alternate work and retrograde strokes in a first path first spring means urging said slide in retrograde movement, cam means journaled on said base and rotatable to engage and move said slide in working strokes, a tool carrier mounted on said slide for guided translation in a second path toward and from said first path, a unitary helicoidal cam and ratchet wheel journaled on said carrier for rotation on an axis parallel with said second path, and engaging said slide, said cam being rotatable to permit advance of said carrier parallel with said second path, pawl means carried by said slide and engageable with said ratchet wheel to rotate the same

70
75

only in response to retrograde movement of said slide on and relatively to said base, and abutment carried by said base for adjustment in and along said first path, said pawl means engaging said abutment, to be moved thereby, as said slide approaches the terminus of its working stroke, and second spring means urging said pawl means into movement rotating said ratchet wheel, as said slide recedes from said abutment in retrograde motion.

6. An attachment as in claim 5, there being a bore in said slide with axis in a plane normal to said second path, said pawl means comprising a plunger slidably fitting said bore, said second spring means engaging and urging said plunger in one direction in and along said bore, a pawl pivoted to said plunger, and a spring urging said pawl into engagement with said ratchet wheel.

7. An attachment as in claim 5, a bar carried by said slide for guided movement in said first path, a connection between said bar and said carrier and operable to retract said carrier from said first axis by and in response to one direction of movement of said bar relatively to said slide, said cam means engaging and moving said bar as said slide approaches the terminus of its working stroke to retract said carrier as aforesaid, said cam means releasing said bar as said slide begins a succeeding working stroke, and means yieldingly urging said bar in its other direction of movement on and relatively to said slide.

8. In a threading attachment for a lathe adapted to mount and rotate a workpiece about the conventional axis of rotation of a lathe, a base, a slide mounted on said base for guided translation in a first path, a carrier mounted on said slide for guided translation in a second path toward and from said first path, a shaft journaled

5
10

in said carrier parallel with said second path, a cam fixed with said shaft and having a helicoidal surface coaxially thereof, a ratchet wheel having successive smooth and toothed peripheral portions and fixed with said cam, a cam follower fixed with said slide, spring means urging said carrier toward said first path to maintain said helicoidal cam surface in contact with said follower, pawl means carried by said slide for reciprocation in a plane normal to said second path and engaging said ratchet wheel to rotate the same only in response to retrograde translation of said slide.

9. An attachment as in claim 8, an abutment adjustable on said base parallel with said first path and positioned to be engaged and reciprocate said pawl means as said slide approaches its final position in a work stroke, said pawl means becoming ineffective on said ratchet wheel when the wheel presents its smooth peripheral portion thereto.
